UNITED STATES PATENT OFFICE

2,509,341

COAXIAL CABLE TERMINATION

Joseph Goldsmith, Lyons, Ill., assignor to American Phenolic Corporation, Chicago, Ill., a corporation of Illinois

Application November 12, 1946; Serial No. 709,344

4 Claims. (Cl. 174—77)

1

This invention relates to coaxial transmission lines and is specifically directed to the provision of an improved coaxial cable termination.

Coaxial lines are required on many types of electronic apparatus and flexible coaxial cable of several standard sizes is commercially manufactured and widely distributed, but so far as is known to this applicant no practical terminal fitting has heretofore been devised. Instead, it is the custom to connect the ends of the cable to other parts of the apparatus by some make-shift arrangement that almost invariably proves unsatisfactory, both in design and construction.

It is, therefore, the aim of the present invention to provide an article of manufacture comprising a fitting adapted to be secured to the end of a coaxial cable as a terminal element. As here disclosed, the fitting not only serves to establish electrical connection with the conductors of the cable, but also seals the cable ends and mechanically anchors the cable in position. In this connection it may be pointed out from a mechanical standpoint it is not only necessary to secure the metallic conductors of the cable but it is also desirable to secure the outer insulating layer of the cable and the woven wire armor surrounding it. Electrically, most satisfactory results are obtained by a direct soldered connection with the conductors, and in the case of the outer conductor it is preferable to have a soldered connection of annular form extending completely around the conductor. A perfect hermetic seal between the central and outside conductors of the cable is also important since it is well known that in electrical apparatus of the type utilizing these cables the entry of any moisture into the coaxial line is detrimental to the operation of the equipment and that for most efficient operation it is essential that the space between the conductors be completely sealed in a moisture proof and air-tight manner. It is also desirable that the general appearance of the fitting be neat and compact and that it be sufficiently rugged to withstand thorough use.

It is therefore the principal object of the invention to provide a coaxial cable termination of improved construction and novel mechanical design, so that the cable ends may be firmly anchored, electrically connected in an ideal manner, and perfectly sealed.

A further object of the invention resides in the provision of a terminal fitting for coaxial lines constructed in such a way that it may be readily applied to the forms of flexible coaxial cable now in commercial manufacture.

2

Another object of the invention resides in the provision of a terminal fitting so constructed that it may be quickly and easily applied to a length of coaxial cable by any workman of ordinary skill, without the use of special tools and without training in special techniques.

A still further object of the invention resides in the provision of a fitting having the features indicated above, yet simple in design, neat and compact in appearance, rugged in construction, and adapted to economical methods of manufacture on conventional types of automatic production machinery.

The foregoing objects are accomplished by the invention here disclosed, since the fitting illustrated in the drawing of this specification and described herein is adapted to be attached to a commercial type of coaxial cable and when attached will securely anchor the cable and in a physical sense, seal the end of the cable, and establish electrical connection with the conductors of the cable. Further, it is so designed that it may be attached to the cable by any ordinary workman without special training or special tools, and in a very few moments time.

In general, the fitting consists of a tubular sleeve with a threaded bore to grip the outer insulation of the cable and a flange and clamping nut to anchor the end of the woven exterior armor of the cable, together with means to secure the outer conductor to the sleeve and an insulator through which a lead from the center conductor may extend. The outer insulation and armor may be secured to the fitting before the electrical connections between either the outer conductor of the cable or the central conductor are soldered, so that the armor and insulation serve to secure the cable to the terminal fitting. Thus any possibility of undue strain on the electrical connections that are later soldered is eliminated.

In the drawing, the single figure is a central sectional view through the cable termination, the cable and fitting being shown in assembled position.

The coaxial cable itself consists of a center conductor 10 comprising several twisted wire strands, surrounded by a thick dielectric layer 11, usually of polyethylene. The layer 11 is in turn surrounded by a tubular outer conductor 12, which ordinarily consists of a woven wire sleeve. The outer conductor 12 is covered by a layer of insulation 13 and woven wire armor 14 surrounds the insulation to protect the cable against mechanical damage.

The fitting with which this invention is par-

ticularly concerned is generally tubular in form and includes a cylindrical sleeve 15 having internal threads 16 to grip the surface of the insulating layer 13 and an external flange 17 threaded to receive a clamping nut 18. The clamping nut is adapted to force a washer 19 against the flange 17 to clamp the extreme end portions 21 of the individual wires of the armor 14 against the flange 17. This serves to mechanically anchor the armor to the fitting, and since the washer 19 need not rotate when the nut 18 is tightened there is no tendency to twist the armor.

It may be mentioned at this point that while the flange 17, washer 19 and nut 18 provide a means for terminating the cable armor and mechanically securing the termination fitting to the armor, yet the fitting is equally well adjusted to application to unarmored cables; and when applied to a cable without the outer layer of woven wire armor is applied in exactly the same manner except that the nut 18 is idle.

The fitting includes a central section 22 which is also of cylindrical form and unitary with the sleeve 15 and flange 17, but of somewhat less diameter than the internal diameter of the threads 16. This section is adapted to closely surround the outer conductor 12 of the cable, and is provided with a number of radial ports 23 extending through the walls of the bore so that solder 20 may be applied through these ports to unite the conductor 12 with the inside surface of the cylindrical section 22. The fitting also includes a cylindrical bore 25 adapted to mount an insulator 26. The insulator is preferably of polystyrene, which has important advantages over glass or ceramic materials in high frequency work, since either glass or ceramic insulators present a marked impedance discontinuity and consequent power loss because of the high dielectric constant and poor power factor of these materials. As the present design uses a low loss bushing, the mismatch and power loss are avoided and proper dimensional proportions are attained. Insulator 26 is further designed with annular serrations to increase the electrical creepage path. This helps to insure high resistance between conductors in the presence of moisture; thus raising the break-down voltage across the termination.

The insulator 26 is fitted in the bore to bear against the shoulder 27 and is hermetically sealed to the fitting by spinning the extreme edge 28 of the fitting inwardly. Since the insulator 26 is formed of polystyrene, when the edge 28 is spun the heat generated by the spinning operation and the pressure exerted by the spinning tool will combine to cause a perfect hermetic seal to be established between the insulator and the metal.

The insulator 26 carries a central ferrule 31 having an orifice 32 at its outer end. These parts are assembled by heating the ferrule and forcing it into a drilled opening in the insulator while hot, so that the simultaneous application of heat and pressure causes a perfect hermetic seal between the metal surface of the ferrule and the plastic surface of the insulator.

The fitting is also provided with a unitary annular flange 33 and a threaded portion 34 so that the cable can be mechanically fastened to other apparatus by inserting the end of the fitting through a mounting bracket and tightening a nut 35 to clamp the bracket between the nut and the flange 33.

To assemble the fitting and install it on a piece of flexible coaxial cable, the cable is first stripped to expose a length of the central conductor 10. The outer conductor 12 and dielectric layer 11 are then both stripped back slightly further, so that each have a surface exposed. If desired, solder may be applied to the surfaces of the conductor 12 so that the woven ends of the wire will not fray, and so that later soldering will be facilitated. The clamping nut 18 and washer 19 are slipped over the end of the cable, and the end of the braided armor 14 is loosened. The cable is then ready for insertion into the fitting.

Before inserting the cable, it is preferable to place a sealing compound 30 inside the bore of the fitting to aid in the establishment of a perfect hermetic seal. Numerous compounds are available for this purpose, but the one known on the market as Dow-Corning Sealing Compound No. 4 achieves excellent results.

The cable may then be inserted into the fitting by passing the central conductor 10 into the ferrule 31 and out through the orifice 32 until the outer insulating layer 13 of the cable is received in the open threaded end of the tubular sleeve 15. The fitting is then threaded to the insulating layer. The individual screw threads 16 will form grooves in the outer surface of the insulation and when the insulation is threaded to the full depth indicated will provide a very effective mechanical grip between the fitting and the insulating layer of the cable. The loose ends of the woven wire armor 14 may now be drawn upwardly around the outside of the tubular sleeve 15 and the washer 19, which has previously been placed in position on the cable, is drawn up to the position shown so that the free ends 21 of the individual wires of the cable armor lie between the washer 19 and the flange 17 and extend outwardly in a generally radial direction. The outwardly extended ends of the wire may now be trimmed to proper length so that the clamping nut 18 can be drawn upwardly and threaded on the flange 17. As the clamping nut 18 is tightened it will force the washer 19 in firm clamping engagement with the ends of the individual wires comprising the cable armor and will thus mechanically anchor the armor as well as the outer insulation of the cable to the fitting.

When the fitting is thus secured to the cable, the exposed portion of the outer conductor 12 will be positioned inside of the central portion 22 of the bore and closely adjacent the interior wall surfaces. As heretofore stated, this surface of the conductor 12 has been tinned by the application of solder so that it may be easily united with the fitting by applying hot solder 20 through the ports 23. Any desired number of ports may be used, but it has been found that four are quite satisfactory and that solder applied through the ports will flow completely around the outside of the conductor 12 to make a firm electrical and mechanical joint all the way around the tube.

The electrical lead from the central conductor 10, which extends through the insulator 26 and through the orifice 32 at the end of the ferrule 31 is also sealed at the orifice by a drop of solder 29 which will unite the several strands of the conductor to the ferrule. The solder will also flow between the individual strands of the conductor to completely seal the orifice against moisture or air. If desired, a conventional type of connecting lug 36 may then be soldered to the free end of the lead.

The foregoing description should make it ap-

parent to those familiar with the problems encountered in coaxial cable installations that the teachings of this invention provide a feasible method of perfecting an efficient cable termination on any of the conventional manufactured forms of flexible coaxial cable. It is also to be noted that the disclosure of this invention shows a cable fitting that is at once simple in construction and well adapted to mass production manufactured on conventional types of production machinery, yet is capable of being installed on conventional cable without special tools and by any ordinary technician. Moreover, the cable termination here disclosed constitutes a distinct advance over previously known installations in that it provides a connection that is not only perfect electrically, but is mechanically strong so that it may be subjected to considerable abuse without damage and will provide a secure physical anchor for the ends of the cable. Moreover, attention is again directed to the fact that this type of termination not only establishes a perfect electrical connection between the conductors of the cable and their associated equipment, but also establishes a moisture-proof and air-tight seal for the space between the conductors of the cable so that the efficiency of operation of the installation cannot be affected by the entrance of vapor, moisture, etc.

The exact structure of the fitting illustrated in the drawing of the specification is believed to be ideal for the purpose of disclosing the inventive thought and is a present preferred form of the invention, now in commercial manufacture. It is to be recognized, however, that the scope of the inventive thought is not limited to the exact structure shown and described, but extends to various possible modifications and should be regarded as limited only by the terms of the appended claims.

Having thus described the invention, what I claim as new and desire to protect by Letters Patent is:

1. As an article of manufacture, a terminal fitting for coaxial cable comprising a single sleeve having an internal bore with threaded surfaces adapted to grip the exterior insulation of a section of coaxial cable and a reduced diameter portion of the bore to closely surround the outer conductor of the cable and adapted to be soldered thereto; said reduced diameter portion of the bore having open ports in its walls so that solder may be introduced from the exterior of the sleeve; an insulator mounted in a position coaxial with the sleeve and hermetically sealed to the sleeve, together with a center ferrule extending through and hermetically sealed in the insulator, said ferrule including a opening adapted to surround an electrical lead extending outwardly from the cable, and having an exposed orifice so that said lead may be sealed to the ferrule by soldering from the exterior of the fitting.

2. As an article of manufacture, a terminal fitting for coaxial cable comprising a single sleeve having an internal bore including surfaces adapted to grip the exterior insulation of a sec-

tion of coaxial cable; a reduced diameter portion of the bore to closely surround the outer conductor of the cable and adapted to be soldered thereto; an insulator mounted in a position coaxial with the sleeve and hermetically sealed to the sleeve, together with a ferrule extending through and hermetically sealed in the insulator, said ferrule including an opening adapted to receive an electrical lead extending outwardly from the cable and adapted to closely surround said lead, so that the lead may be sealed to the ferrule by soldering.

3. In a termination for a coaxial cable having a central conductor, a dielectric layer and an outer tubular conductor surrounded by insulation and armor, the combination of a fitting having a sleeve portion surrounding and directly engaging the insulation, means for securing the armor outside of said sleeve portion, means for securing the outer tubular conductor inside of said fitting, and an insulator carried by said fitting and surrounding a portion of the central conductor of the cable extending out of the fitting.

4. As an article of manufacture, a terminal fitting for coaxial cable comprising a single sleeve having an external flange and external screw threads adjacent the flange for securing the fitting to a mounting bracket; a second flange spaced apart from the mounting flange with external threads thereon and a cooperating nut to clamp the armor layer of a cable in position on the fitting; an internal bore through the fitting with threaded surfaces at one end adapted to grip the exterior insulation of a section of coaxial cable, and a cylindrical mounting bore at the opposite end; an insulator mounted in said bore and hermetically sealed therein, said insulator extending substantially beyond the end of the fitting and having a center ferrule hermetically sealed within the insulator throughout its entire length, with an opening through the ferrule adapted to surround an electrical lead extending outwardly from the cable, and an exposed orifice so that the lead may be sealed to the ferrule by soldering from the exterior of the fitting.
